UNITED STATES PATENT OFFICE

146,559

DESIGN FOR A STRADDLE TRUCK

Henry N. Dimick, Portland, Oreg., assignor to
Hyster Company, Portland, Oreg., a corpora-
tion of Oregon

Application October 9, 1944, Serial No. 115,688

Term of patent 14 years

(Cl. D14—3)

To all whom it may concern:

Be it known that I, Henry N. Dimick, a citizen of the United States and a resident of Portland, in the county of Multnomah, State of Oregon, have invented a new, original, and ornamental Design for a Straddle Truck, of which the following is a specification, reference being had to the accompanying drawings, forming a part thereof.

In the drawings:

Figure 1 is a side elevational view of a straddle truck embodying my new design.

Figure 2 is a top plan view of the truck shown in Figure 1.

Figure 3 is a front elevational view of the truck shown in Figure 1.

Figure 4 is a rear perspective view of the straddle truck shown in Figure 1.

The characteristic features of my design reside in the portions shown by means of full lines in the drawings.

The side of the device opposite that shown in Figure 1 of the drawings is substantially the same as illustrated.

I claim:

The ornamental design for a straddle truck, as shown and described.

HENRY N. DIMICK.
